UNITED STATES PATENT OFFICE.

WILLIAM HENRY BRECKNELL, OF WESTON-SUPER-MARE, ENGLAND.

LOCKING DEVICE FOR CYCLE AND SIMILAR LAMP BRACKETS.

Application filed December 6, 1926, Serial No. 152,872, and in Great Britain November 23, 1925.

This invention relates to improvements in cycle and similar lamp brackets and consists of providing a locking device for preventing the theft of cycle or similar suspended lamps.

Many forms of such lamp brackets have been suggested and of these a bracket has been proposed in which the portion of the bracket which enters the lamp socket is constructed long enough to protrude some distance through same and the protruding end is designed to receive a head carrying a spring lock which can only be removed by the use of a key.

The present invention is an adaptation of the last mentioned bracket. The bracket is provided with a tongue extension coplanar therewith having a series of wards along one of its edges and of such dimensions as will allow of the extension being readily passed through the lamp socket.

In order to prevent removal of the lamp from this bracket a locking member is provided in the form of the barrel portion of a permutation lock carrying tumblers of larger external diameter than the aperture of the lamp socket. This lock is placed upon the protruding end of the tongue when the lamp is in position on the bracket.

My invention is illustrated by way of example in the accompanying drawings, in which—

Figure 1 shows a bracket with a vertical tongue extension adapted to receive the permutation lock, and

Figure 2 shows an alternative form in which a horizontal tongue is employed.

Referring now to the drawings; 1 indicates the bracket and 2 the extension provided with a series of wards 3 along one edge. The tongue 2 is adapted to receive the member carrying the tumblers of the permutation lock 4, the tumblers being of a larger external diameter than the aperture of the lamp socket. Any suitable type of permutation lock can be employed and its operation requires no description.

Figure 2 shows a modification in which the tongue extension 2' is horizontal. The parts which correspond with those in Figure 1 are designated by the same reference characters primed.

Finally it should be mentioned that I am aware that permutation locks for such purposes as locking handle bars of bicycles, have been suggested.

What I claim is:—

The combination of a bracket having an integral tongue extension provided with a series of wards, on one edge thereof, said extension adapted to pass through an opening in a lamp socket, and a removable member carrying a plurality of permutation tumblers coacting with said wards, the diameters of said tumblers being larger than the opening in the lamp socket.

In testimony whereof I have signed my name to this specification.

WILLIAM HENRY BRECKNELL.
